DESIGN.

E. C. MOORE.

Jewelry-Boxes.

No. 6,773.

Patented July 15, 1873.

Fig. 1.

Fig. 2.

UNITED STATES PATENT OFFICE.

EDWARD C. MOORE, OF YONKERS, ASSIGNOR TO TIFFANY & CO., OF NEW YORK, N. Y.

DESIGN FOR JEWELRY-BOX.

Specification forming part of Design No. 6,773, dated July 15, 1873; application filed June 14, 1873.

To all whom it may concern:

Be it known that I, EDWARD C. MOORE, of Yonkers, in the county of Westchester and State of New York, have invented a new and original Design for Paper Boxes for Jewelry, &c., of which the following is a specification:

Figure 1 is a side elevation, and Fig. 2 is a transverse section of a paper box constructed according to my design; which consists of the oval form of the top A of the box, either with or without the projecting edges B of the top and bottom.

The boxes will be made of fine stiff paper or Bristol-board, and are intended for jewelry and other fine goods.

I claim as my invention—

The design for jewelry-boxes formed by the oval top A, with the projecting edges B of the top and bottom, as herein shown and set forth.

EDWARD C. MOORE.
